(57) **CLAIM**

The ornamental design for a medical pump holder, as shown and described.

DESCRIPTION

FIG. 1 is a top view of the design for a medical pump holder. FIG. 2 is a front view thereof.

FIG. 3 is a bottom view thereof.

FIG. 4 is a right side view thereof.

FIG. 5 is a rear view thereof.

FIG. 6 is a left side view thereof; and,

FIG. 7 is a perspective view thereof.

The broken line showing of parts of the drawings is included for the purpose of illustrating use and environment and forms no part of the claimed design.
